The ornamental design for a four-head gas fryer, as shown and described.

DESCRIPTION

FIG. 1 is a frontal view of a four-head gas fryer, according to my design.

FIG. 2 is a left side view of a four-head gas fryer of FIG. 1. FIG. 3 is a right side view of the four-head gas fryer of FIG. 1; and,

FIG. 4 is a top view of the four-head gas fryer of FIG. 1. In the drawings, the broken lines are for illustrative purposes only and form no part of the claimed design.

The surfaces or portions of the article not shown in the drawing or described in the specification form no part of the claimed design.
